(57) **CLAIM**

The ornamental design for a kart, as shown and described.

DESCRIPTION

FIG. 1 is a front perspective view of a kart, which embodies my design.

FIG. 2 is a front view of the kart of FIG. 1.

FIG. 3 is a rear view of the kart of FIG. 1.

FIG. 4 is a left side view of the kart of FIG. 1.

FIG. 5 is a ride side view of the kart of FIG. 1.

FIG. 6 is a top view of the kart of FIG. 1; and, FIG. 7 is a bottom view of the kart of FIG. 1.

The broken lines immediately adjacent the shaded areas represent the bounds of the claim and all other broken lines represent portions of the kart that form no part of the claimed design. None of the broken lines form a part of the claimed design.

1 Claim, 5 Drawing Sheets
